UNITED STATES PATENT OFFICE.

BENJAMEN PETERSON, OF SOUTH CHICAGO, ILLINOIS.

HINGE.

SPECIFICATION forming part of Letters Patent No. 729,406, dated May 26, 1903.

Application filed January 27, 1902. Serial No. 91,486. (No model.)

To all whom it may concern:

Be it known that I, BENJAMEN PETERSON, a citizen of the United States, residing at South Chicago, in the county of Cook and State of Illinois, have invented certain new and useful Improvements in Hinges; and I do hereby declare the following to be a full, clear, and exact description of the invention, such as will enable others skilled in the art to which it applies to make and use the same.

My invention relates to a novel construction in a hinge, the object being to provide a device of this character having a self-contained gage by means of which its position on the parts to be hinged together can be readily determined without the use of other marking or measuring tools; and it consists in the features of construction and combinations of parts hereinafter fully described and claimed.

In the accompanying drawings, illustrating my invention, Figure 1 is a view in elevation of a hinge constructed in accordance with my invention. Fig. 2 is a section of same on the line 2 2 of Fig. 1. Fig. 3 is a section of same on the line 3 3 of Fig. 1. Fig. 4 is a sectional view showing the hinge secured in place.

In hinging two members together, such as a door and jamb, it is essential that the pivots of the hinges are parallel with the adjacent edges of the parts hinged and in exact alinement with each other, as otherwise said hinges are subjected to undue strain, and the result is that the increased friction will cause disagreeable squeaking. In determining the position of the hinge great difficulty is frequently occasioned in marking the door or jamb preparatory to cutting the recess for the leaf, and as

a result much labor is frequently wasted. My invention is designed to overcome such difficulties, and to this end I provide each leaf A of the hinge with a flange B adjacent to and parallel with the pivot C, said flange being adapted to perform the functions of a square in an obvious manner. The two horizontal edges and the outer vertical edge of each leaf are further provided with a flange D of less depth than the flange B, but extending in the same direction, said flanges being preferably sharp on their outer ends, so that when the leaf is placed in position on the part to which it is to be secured the place can be marked accurately by tapping on said leaf with a hammer, whereby said flanges D will indent the wood. The flanges B will obviously enable the operator to so secure the leaves to the members to be hinged as to bring the pivots into the desired position relatively to the door or other member, not only squaring the leaves, but also acting as a stop to prevent either leaf from being secured too far inwardly.

I claim as my invention—

In a hinge, the combination with the leaves of flanges mounted on the inner edges of said leaves and extending parallel to the length of the hinge, and flanges of a less depth than the other flanges formed on the top, bottom and sides of the leaves, and having their outer edges pointed.

In testimony whereof I affix my signature in presence of two witnesses.

BENJAMEN PETERSON.
